UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

COLLATED MANIFOLD-PACK.

1,369,312.

Specification of Letters Patent. Patented Feb. 22, 1921.

Application filed May 22, 1917. Serial No. 170,157.

To all whom it may concern:

Be it known that I, JOHN A. WHERRY, a citizen of the United States, residing in New Orleans, in the parish of Orleans and 5 State of Louisiana, have invented certain new and useful Improvements in Collated Manifold-Packs, of which the following is a specification.

My invention relates to means for facilitating the grouping or collating of work-sheets preparatory to their introduction into the typewriting machine.

According to my invention, one of the work-sheets may be used as a backing or 15 holding sheet upon and in reference to which other work-sheets may be collated.

In continuous ledger-posting, each ledger-sheet is accompanied by the regular monthly statement for the customer during the writing of all entries until the end of the current month. The ledger-sheet and its attached statement are usually stored in a temporary binder until the end of the month, at which 20 time the statement is removed from the ledger-sheet and sent to the customer.

The record of each transaction is type-written upon the invoice (which is usually the top or original sheet; and by means of carbon sheets is simultaneously recorded 25 upon the statement and ledger-sheets. The invoice or bill is then removed and immediately sent to the customer, and the statement-sheet and ledger-sheet are set aside. When the next transaction takes place, a 30 new invoice is collated upon the statement and ledger-sheets. Hence, the various transactions properly follow each other upon the statement-sheet and ledger-sheet, since the first line of each new invoice follows the last previous entry on the statement and ledger-sheets.

I arrange that one of the sheets, in this instance the ledger-sheet, also acts as the backing or collating sheet. The semi-permanent or statement-sheet is caught upon the ledger-sheet, the statement-sheet having holding members in the form of small tongues which engage openings or eyes formed in the ledger-sheet and hold the 45 statement in proper position relatively thereto. These tongues extend in a row 50 down the side of the work-sheet, and may

be arranged at both side edges of the sheet. The statement is thus held upon the ledger-sheet in the desired register therewith.

The ledger-sheet is preferably folded over at the side, so as to form a flap which serves to hold all the sheets thereto and protects the coupling points of the sheets.

The ledger-sheet is preferably perforated at this fold, so as to form small slits or eyes into which the tongues of the statement-sheet may be caught. An additional flap or cover may be provided on the ledger-sheet to protect the tongues from injury.

The invoice-sheet, which is to be collated upon the statement and ledger-sheets, is usually too narrow to extend clear across the ledger-sheet, and, therefore, must be supported by only one of its side edges. I, 70 therefore, make the holding members on the invoice in the form of hooks or claws which enter into the ledger-sheet perforations or eyes and provide a more secure connection between the two than would be secured by 75 tongues. These hooks or claws may extend downwardly through the eyes of the ledger-sheet, thereby forming a secure connection for holding the invoice-sheet close to the side edge of the folded portion of the 80 ledger-sheet.

The statement and the invoice-sheets may thereafter be torn along perforations provided down the side margins, to remove the marginal portions having the holding members whereby they are attached to the 85 ledger-sheet.

To aid in collating the sheets, the writing lines on each sheet are numbered, so that if the last line of writing previously done appears, for example, on the fifth line of the statement-sheet, line marked "1" on the invoice-sheet would be placed directly over line "6" on the statement-sheet.

It will be understood that at the end of 95 the month covered by the items in the statement, the statement is removed from the ledger-sheet and sent to the customer. The next month's statement is then collated upon the ledger-sheet, so that the first 100 line of writing thereon follows the last line of writing upon the ledger-sheet; the line numbers on the ledger-sheet and statement sheet aiding in collating these sheets in the

same manner as in the case of the invoice and statement.

Other features and advantages will hereinafter appear.

5 In the accompanying drawings,

Figure 1 is a perspective view of my invention, showing the collated sheets on the platen of a typewriting machine, the platen being indicated in dot-and-dash lines.

10 Fig. 2 is a fragmentary sectional view of the work-sheets, showing, in detail, the tongues on the statement-sheet and hooks or claws of one specific form on the invoice-sheet.

15 Fig. 3 is a view of a modification of my invention, showing the statement-sheet as having its tongue only at one side edge; the other side edge of the sheet being engaged with a folded portion of the ledger-sheet.

20 Fig. 4 is a view of the work-sheets, which shows an invoice-sheet provided with hooks or claws of a different specific form for engaging the ledger-sheet.

25 A ledger-sheet 10, in the present embodiment of my invention, is also used as a backing or collating sheet, upon which a statement 11 and an invoice 12 may be assembled, and inserted as a unit into the typewriting machine, and then fed by feed rolls 13 around with the platen 14, to position to receive type impressions by the type-bars 15.

To hold it in position, the statement-sheet 11 is cut out at both side edges, so as to form 35 tongues 16. These tongues 16 may be located down the side of the sheet 11, so that there is one for each line of writing thereon. When the statement-sheet 11 is properly placed upon the ledger-sheet 10, the tongues 40 16 thereon are passed through openings 17, formed by circular perforations in the ledger-sheet 10, thus providing an interengaging relation between the side edges of the statement and ledger-sheets whereby 45 relative endwise movement of one with respect to the other is prevented. These perforations are arranged at the side of the ledger-sheet, and one is provided for each line-space thereof. These tongues 16 may 50 be passed through any of the openings 17.

The ledger-sheet 10 is folded at 18, the fold passing through the center of the openings 17, thus changing the perforation to an open slit, through which the tongues 16 55 may be passed. A flap 20, formed by the folding of the work-sheet at 18, extends slightly over the margin of the statement-sheets, and aids in preventing the sheets from bulging out, and thus withdrawing the 60 tongues 16 from the slits or eyes 17. The ledger-sheet is again folded at 19 and 21, so as to form a shield, guard or housing 22; which guard is made up of two portions 65 extending one along each side of the fold or crease 21 and incloses or overlies the open-

ings and tongues or equivalent holding members; one of said portions lying upon each side of said members, as will be appreciated; it being obvious that the shield aforesaid extends along the fold formed at 70 21 and overlies and protects the tongues 16 from being damaged.

In some kinds of billing work, it is desired that certain data be written only upon the statement and ledger-sheets, and not 75 upon the invoice-sheet. For this and other reasons, the invoice-sheet is usually considerably narrower than the statement and ledger-sheets. The invoice-sheet, therefore, does not extend from one side of the ledger-sheet to the other, and, consequently, the invoice-sheet 12 can only be supported by the ledger-sheet 10 at one side thereon. In order that this side of the invoice sheet will be more securely held in place when collated 80 than it would be held by straight tongues like the tongues 16, the invoice-sheet 12 is cut out at one of its side edges, so as to provide hooks or claws 23 thereon. These hooks or claws 23 extend downwardly and 85 may be passed through the slits 17 in the ledger-sheet 10. When placed in position on the ledger-sheet 10, the hooks or claws 23 of the invoice-sheet 12 hook onto the ledger-sheet and the invoice-sheet is thereby supported in a horizontal position. These hooks or claws 23 pass through the slits 17 in the same manner as the tongues 90 16, although they must be inserted with 95 a slight downward movement.

With this arrangement, it will be seen that the weight of the invoice sheet will cause it to be pulled by gravity close to the side edge of the fold 18, and thus automatically align itself with the ledger and statement-sheets. This arrangement also is advantageous in that the operative may remove the invoice-sheet by imparting a diagonal movement thereto; and should the operative instead of grasping the invoice-sheet 12 accidentally grasp the statement-sheet 11, the form and arrangement of the tongues 16 thereof will prevent its removal, as the statement-sheet must be bulged out at the center slightly to remove the tongues 115 from the slits 17.

It will be understood that sheets of transfer material, such as carbon sheets, are to be placed between the bill and statement; and if so desired, the carbon sheets may be provided with attaching portions in the form of tongues or claws similar to those on the work-sheets.

For some classes of work, it may not be desired to provide the tongues 16 on both 125 sides of the statement-sheet 11. In this case, the statement-sheet, as seen in Fig. 3, would only be coupled to the ledger-sheet by the tongues 16 at one side, the other side of the statement-sheet being in engagement 130

with the folded portion 18 of the flap 20 on the ledger-sheet 10, and thus held in alignment on the ledger-sheet.

In Fig. 4, the invoice-sheet 12 is provided with holding members in the form of hooks or claws 24 of a somewhat different form at its side edge. These hooks or claws 24 extend downwardly in the same manner as the hooks or claws 23, and when passed through the opening 17 in the ledger-sheet, drop down slightly and hook onto the ledger-sheet at the fold 18. Work-sheets provided with such claws 24 may be used when it is desired to have a more positive connection with the ledger-sheet 10 than is obtained by the use of sheets having the hooks or claws 23.

It will be seen that after the hooks or claws 24 have engaged the fold 18 of the work-sheet 10, the extremity 25 of the hook or claw prevents the sheet from being removed by being drawn straight away from the fold 18 to the right, as seen in Fig. 4.

To assemble the sheets upon the backing sheet, the operative lays the backing sheet 10 upon the table and passes the tongues 16 on the statement-sheet 11 beneath the flaps 20 through the openings 17 on the ledger-sheet 10. The hooked or clawed edge of the bill or invoice 12 is then passed beneath the flap 20 until the hooks or claws 23 or 24 thereon extend through the openings 17 on the ledger-sheet 10. The sheets are so assembled that the first line to be written on the statement-sheet will follow the last line written on the ledger-sheet, and so that the first line to be written on the invoice-sheet will follow the last line written on the statement-sheet. To aid the operative in doing this, the lines of writing on the sheets are numbered at 26, the numbers for the ledger-sheet being provided upon the flap 20.

The work-sheets after being collated are taken as a unit preferably by the side edges, (so as to hold the flaps 20 firmly against the sheets), and inserted into the machine. The sheets are preferably placed in the machine so that one of the usual feed rolls 13 will bear against each of the flaps 20 at the side of the ledger-sheet, and cause the flaps to tightly bind the work-sheets, and thereby hold the bill and statement firmly against the backing or ledger-sheet. It will be understood that the other usual feed rolls 13 may be located in their usual position intermediate the feed rolls 13 which bear upon the flaps 20 to perform their usual function.

The work-sheets 10, 11 and 12 may be perforated at 27 along their side edges, so that the edge portions, which are only used for collating purposes, may be easily removed after the entire work has been completed on the sheets.

It should be understood that I do not limit the present invention as simply being

applied to the form of work above described, that is, work on ledger-sheets, statements and bills, but that my invention is equally well applicable to many other forms of work. The above example of ledger posting was selected from the numerous other styles of work, to which my invention is applicable, because of its simplicity. It will be further understood that where the sheet 10 is referred to as the ledger-sheet, any other style of backing sheet may be used. The same applies to the statement-sheet 11 and the invoice-sheet 12.

Variations may be resorted to within the scope of the invention, and portions of the improvements may be used without others.

Having thus described my invention, I claim:

1. The combination with a main work-sheet, of a supplementary work-sheet having tongues engaging the main work-sheet along the side edges thereof, and an additional work-sheet having claws engaging the main work-sheet at one side edge.

2. A work-sheet having spaced openings arranged along both its side edges, and having said edges folded to provide flaps overlying the side portions of the sheet, the fold or crease thus produced passing through the openings aforesaid.

3. The combination with a backing sheet upon which work-sheets may be collated, of a work-sheet collated with and the side edges of which interengage with the backing sheet along both side edges thereof, and another work-sheet having means at one of its side edges for holding the same to the backing sheet.

4. A work-sheet having spaced openings arranged along its side edge, and a guard carried by said sheet and extending over said openings.

5. A work-sheet having spaced openings arranged along its side edge, and having said edge folded to provide a flap overlying a side portion of the sheet, the fold or crease thus produced extending through the openings aforesaid, and a folded guard extending along and overlying both the front and back of the side portion of the sheet.

6. The combination with a backing sheet, of a work-sheet having means to interengage with a side edge of and be held to the backing sheet, and another work-sheet having means for holding and catching to the backing sheet, said backing sheet being provided with a guard for protecting the assembled sheets and the backing sheet at the point of coupling.

7. The combination with a flexible main work-sheet, of a supplementary flexible work-sheet having means whereby it is collated upon and interengaged with the main work-sheet, and an additional flexible work-sheet having means engaging and hooking

onto the main work-sheet, said sheets comprising a manifold pack adapted to be fed about a rotatable platen.

8. The combination with a main work-sheet upon which other work-sheets may be collated, of a supplemental work-sheet having means whereby it is collated upon and interengaged along both its side edges with the main work-sheet, and an additional work-sheet having means engaging the main work-sheet along one edge of the said main work-sheet, whereby said additional work-sheet is held in place along one only of its side edges.

15 9. As an article of manufacture, a combined backing and work-sheet having means adjacent its side edge whereby another sheet may be collated thereon and interengaged therewith, and a guard adjacent said side edge and overlying the means for providing said interengaging connection.

10 10. As an article of manufacture, a work-sheet having extending portions spaced along its side edge whereby said sheet may be attached to another sheet, said extensions being in the form of downwardly-inclined hooks.

11. The combination with two separate work-sheets, of means carried by said work-sheets for effecting an interengaging relation between them along both their side edges and at predetermined points, the points of engagement being variable at will.

12. The combination with two separate work-sheets, of means comprising elements formed from parts of said sheets for effecting an interengaging relation between them at predetermined points, the points being variable at will, and a guard overlying and serving to protect the interengaging connection between said work-sheets.

13. The combination with two separate work-sheets, of means for interengaging the two sheets one with the other at predetermined points along both their side edges, the points being variable at will, and said means being carried by the sheets.

14. The combination with two separate work-sheets, of means formed from portions of said two sheets for effecting an interengaging relation between them, said means comprising two sets of devices, one set on one sheet and one on the other, said two sets of devices being engageable separably and 55 reengageable in a different relationship from the first engagement without affecting the devices, and a guard carried by one of said work-sheets and overlying the interengaging means whereby said sheets are secured together.

15. The combination with a work-sheet, the side edges of which are folded, and a second work-sheet, the side edges of which are inclosed by the folds of the first sheet, 65 of interengaging means arranged along both

sides of said sheets for preventing relative displacement of the two sheets lengthwise of said folds, said interengaging means being carried wholly by the two sheets and comprising two sets of co-acting devices at each side of the sheets, one set on one sheet, and one set on the other, the two sets being variably engageable at will.

16. The combination with a work-sheet, the side edge of which is folded, and a second work-sheet, the side edge of which lies within the fold of said first sheet, of interengaging means spaced along said side edges for preventing relative displacement of the two sheets lengthwise of the fold, said interengaging means being carried wholly by the two sheets and comprising two sets of co-acting devices, one set on one sheet, and one set on the other, the two sets being variably engageable at will, and a shield carried by said folded sheet and extending along and overlying the means whereby the interengaging connection is provided between said sheets.

17. In combination, a folded work-sheet, the fold of said sheet being provided with a series of perforations, a second work-sheet having at its edge a series of projections engageable in said perforations to thereby attach the two sheets together, and a guard carried by said folded work-sheet and inclosing said perforations and projections.

18. In combination, a work-sheet folded along both its side edges, and a second work-sheet, the side edges of which lie within the folds aforesaid, said folds being provided each with a series of perforations and the said side edges of the second sheet with a series of projections engageable variably in said perforations to interengage the two sheets in different relationships.

19. In combination, a work-sheet folded along both its side edges, a second work-sheet, the side edges of which lie within the folds aforesaid, said folds being provided each with a series of perforations and the said side edges of the second sheet with a series of projections engageable variably in said perforations to interengage the two sheets in different relationships, and two guards extending one along each of the side edges of said folded work-sheet and inclosing the perforations thereof and the projections of said second-mentioned work-sheet.

20. A manifold pack comprising two interengaging work-sheets, one provided with openings spaced along each of its side edges, and the other with projections spaced along both side edges and adapted to variably enter said openings.

21. A manifold pack comprising two interengaging work-sheets, one provided with openings spaced along each of its side edges, and the other with projections spaced along 130

- both side edges and adapted to variably enter said openings, said sheets being provided with guards along their side edges to protect the interengaging portions thereof.
5. 22. The combination with two separate work-sheets, of means carried by said sheets and arranged along both side edges of each of them for variably fixing the side edges of said sheets in predetermined relationships, and folded guards extending along the side edges of said sheets and inclosing the fixing means aforesaid.
10. 23. The combination with two separate work-sheets, of means carried in part by one sheet and in part by the other for variably fixing the relationship between said sheets from time to time in accordance with the requirements for readjustment, said fixing means extending along both sides of said sheets, and suitable indicating means being provided in connection with said fixing means to facilitate the bringing of the parts into desired relationships.
15. 24. The combination with a main work-sheet, of one or more supplemental work-sheets in collated relation therewith, said main work-sheet having perforations at the side thereof, a fold passing through the perforations, and a flap extending inwardly from said fold and outwardly past said fold and thence back to the work-sheet, said outward portion extending past the fold and
20. forming a housing or shield for protecting attaching portions of the collated supplemental sheets, said attaching portions passing through the perforations at the fold of the work-sheet.
25. 25. The combination with a backing sheet, of a work-sheet having means at one side edge for engaging the backing sheet at one side edge whereby it may be attached thereto, and a flap at the other side edge of the backing sheet to engage the other side edge of the work-sheet and thus hold the work-sheet and backing sheet in collated relation.
30. 26. The combination with a main sheet, of a supplementary sheet and a temporary supplementary sheet, said main sheet having means to be engaged by the supplementary sheet, and the temporary supplementary sheet having means whereby it may engage the main work-sheet, said last-mentioned means being of a different nature from the means upon the supplementary work-sheet, whereby the supplementary work-sheet and the temporary supplementary work-sheet are collated and removed from the main sheet in different manners.

JOHN A. WHERRY.
